UNITED STATES PATENT OFFICE.

JOHN GOOD, OF NEW YORK, N. Y.; JULIA E. GOOD ADMINISTRATRIX OF SAID JOHN GOOD,
DECEASED.

TWINE-MACHINE.

No. 902,813.

Specification of Letters Patent.

Patented Nov. 3, 1908.

Application filed May 19, 1906. Serial No. 317,677.

To all whom it may concern:

Be it known that I, JOHN GOOD, a citizen of the United States, and resident of the borough of Brooklyn, in the city and State of New York, have invented new and useful Improvements in Twine-Machines, of which the following is a specification.

The object of my present invention is to provide certain improvements in the construction, form and arrangement of the several parts of a twine machine whereby a very compact and efficient machine is provided for producing twine in a consecutive series of operations from the bale to the bobbin.

15 A further object is to provide a mechanism in which the choking of the fiber in the nippers will automatically slow up the different mechanisms as required.

In the accompanying drawings, Figure 1 is the left hand side view of the machine, Fig. 2 is the right hand side view of the machine, Fig. 3 is the vertical longitudinal section through the machine, Fig. 4 is a top plan view, Fig. 4^a is a detail view showing 20 one pawl and ratchet drive connection in the friction brake mechanism, Fig. 4^b is a detail view showing the other pawl and ratchet drive connection in the friction brake mechanism, Fig. 4^c is a detail section on an enlarged 25 scale of a portion of the friction brake mechanism, Fig. 5 is a detail horizontal section through the liquid containing vessel of the flier, Fig. 6 is a detail horizontal section through the flier in another plane, Fig. 7 is a 30 detail side view of one of the hackling cylinders, Fig. 8 is a transverse central section through the same, and Fig. 9 is a face view of one of the pair of stationary box cams for 35 controlling the movements of the gill pins.

40 The framing of the machine is denoted by 1.

The main drive shaft is denoted by 2, which shaft is provided with a pulley 3 around which a belt 4 passes for imparting 45 a rotary movement to the shaft 2 at the desired speed from any suitable source of power, not shown herein. This shaft 2 has a chain and sprocket driving connection 5, 6, and 7, with a cross shaft 8. This cross shaft 8 has 50 a belt and pulley driving connection 9, 10, 11 with the shaft 12 of the nipper roll 13.

A funnel guide 14 is arranged in position to direct the fiber from the gill pins 15 of the upper one of three hackling cylinders 16, 17, 55 18, between the nipper roll 13 and the nipper roll 19, which latter roll is mounted in a

swinging bearing 20. A third nipper roll 21 is held yieldingly in engagement with the main nipper roll 13, from which rolls the 60 twine is fed to the spindle and flier 22, 23. The spindle 22 is provided with the usual bobbin 24. The flier 23 is rotated from the main drive shaft 2 through a bevel gear connection 25, 26, with a shaft 27, which shaft 65 is provided with a sliding sleeve 28 having a feather and groove connection therewith, said sleeve 28 having a spur gear 29 which meshes with a spur gear 30 fixed to the flier 23.

The vertically reciprocating movement of the flier is imparted to it from the shaft 2 through a worm and gear connection 31, 32, with the cross threaded reverse screw 33 which carries the traverse nut 34, which traverse nut has an arm 35 engaged with the flier 23.

75 The rotary movement of the spindle 22 is retarded by providing it with vanes 36 located in a vessel 37 at the base of the spindle and flier, which vessel is arranged to contain 80 a liquid in which the vanes are immersed.

The rolls for feeding the fiber into the machine are denoted by 38, 39, the roll 38 being driven by a flexible driving connection and pulleys 40, 41, 42, from the shaft 43 of one of a pair of crimping rolls 44, 45, interposed between the hackling cylinders 17 and 18. The fiber as it leaves the feeding rolls 38, 39, passes around an idler reel 46 and from thence up through a funnel guide 47 into engagement with the gill pins 15 on the hackling cylinder 18. The fiber as it leaves the hackling cylinder 18 passes through the crimping rolls 44, 45, and from thence through a funnel guide 48 into engagement 90 with the gill pins 15 on the hackling cylinder 17. From the hackling cylinder 17 the fiber is fed directly to the gill pins 15 on the hackling cylinder 16.

95 The shaft 43 of the crimping roll 44 is driven from the shaft 49 of the friction brake mechanism through a flexible connection 50 and pulleys 51, 52.

The shaft 53 of the hackling cylinder 16 is driven from the shaft 49 through a chain 54 and sprocket wheels 55, 56. The shaft 57 of 105 the hackling cylinder 17 is driven from the shaft 53 of the hackling cylinder 16 through a chain 58, sprocket wheels 59, 60, on the shafts 53, 57, and an idler sprocket 61 on a stud shaft 62.

110 The shaft 63 of the hackling cylinder 18 is driven from the shaft 53 of the hackling cyl-

inder 16 through a flexible connection 64 and pulleys 65, 66.

The cone member of the friction brake mechanism is denoted by 67, and the cup member by 68. The shaft 69 of the friction brake is driven through a flexible connection 70 and pulleys 71, 72, from the cross shaft 8. The shaft 69 of the friction brake is also arranged to drive the intermediate shaft 73 of the friction brake mechanism through a chain 74 and sprocket wheels 75, 76, the sprocket wheel 76 having a pawl and ratchet connection 77, 78, with the intermediate shaft 73.

15 The cup member 68 of the friction brake has a driving connection of a different speed with the shaft 73 through a chain 80, sprocket wheels 81, 82, the sprocket wheel 82 having a pawl and ratchet driving connection 83, 84, with the shaft 73. This intermediate shaft 73 has a driving connection with the shaft 49 through a chain 85 and sprocket wheels 86, 87.

Under ordinary circumstances the intermediate shaft 73 is driven from the shaft 69, through the cup member 68, sprocket wheel 81, 82, and sprocket chain 80.

A brake band 88 encircles the cup member 68 of the friction brake, which brake band, when set, will stop the rotation of the cup member 68 thus causing the shaft 73 to be driven through the chain 74 from the shaft 69. In this case the ratchet 84 will travel around freely beneath its pawl 83. This brake band 88 is operated by the choking of the fiber between the nipper rolls 13 and 19 as follows:—As the swinging bearing 20 is moved upwardly by the nipper roll 19 being forced away from the nipper and roll 13 by the choking of the fiber between the two, the bearing 20 will lift a cross arm 89, the free end of which cross arm is attached to a flexible connection 90 which passes around idler pulleys 91, 92, and from thence upwardly into engagement with one arm 93 of a two armed rocking lever pivoted at 94, the other arm 95 of which lever is attached to the free end of the brake band 88.

An annular series of groups of gill pins 15 is provided for each of the hackling cylinders, which gill pins are brought into and out of engagement with the fiber at the proper times as follows:—Each hackling cylinder has annular series of radially elongated slots 96, 97, in its end walls in which slots the gill pin bars 98 are fitted to slide radially. The gill pins 15 are fitted to slide radially through holes 99 in the periphery of the cylinder.

Stationary box cams 100, 101, are fixed to the framework adjacent to the ends of the cylinder, which box cams have corresponding grooves 102, 103, in their inner faces, in which grooves the ends of the gill pin bars 98 are located. The shape of these cam grooves 65 is such that the pins on each cylinder will be

1 moved outwardly into engagement with the fiber and then moved inwardly out of engagement with the same at predetermined points in the rotations of the several cylinders.

70

It is to be understood that the different driving connections between the several parts need not necessarily be in the form shown and described herein but may be of any well known and approved form capable 75 of transmitting motion from one part to another.

It will be seen that a twine machine constructed, arranged and operated as hereinabove described, occupies an extremely 80 limited flooring space compared with the results accomplished, viz; the feeding of the fiber from the bale into the machine, the combing out of the same, the twisting of the twine and the winding of the twine onto the 85 bobbin. It will also be seen that a uniform thickness of twine is insured for the reason that when any undue amount of fiber is being fed to the nipper rolls, the speed of the several mechanisms will be automatically reduced until the amount of fiber being fed to the nipper rolls is brought out to a predetermined amount.

What I claim is:—

1. A twine machine comprising a main 95 driving shaft, a spindle and flier mechanism driven therefrom, a cross shaft, a nipper mechanism and a friction brake mechanism both driven from said cross shaft, hackling cylinders and fiber feeding means therefor 100 both driven from the friction brake mechanism, the said friction brake mechanism being under the control of the nipper mechanism whereby the speed of the several mechanisms will be automatically reduced when an undue amount of fiber is fed to the nipper mechanism.

2. A twine machine comprising a main driving shaft, a spindle and flier mechanism driven therefrom, a cross shaft, a nipper 110 mechanism and a friction brake mechanism both driven from said cross shaft, hackling cylinders and crimping rolls both driven from the friction brake mechanism, fiber feeding means driven from the crimping rolls, 115 said friction brake mechanism being under the control of the nipper mechanism whereby the speed of the several mechanisms will be automatically reduced when an undue amount of fiber is fed to the nipper mechanism.

In testimony, that I claim the foregoing as my invention, I have signed my name in presence of two witnesses, this 17th day of May 1906.

JOHN GOOD.
